UNITED STATES PATENT OFFICE.

ALBERT F. FIFIELD, OF NEWARK, NEW JERSEY, ASSIGNOR TO THE SINGER MANUFACTURING COMPANY, A CORPORATION OF NEW JERSEY.

STITCH-FORMING MECHANISM FOR CHAIN-STITCH SEWING MACHINES.

1,316,022.

Specification of Letters Patent. Patented Sept. 16, 1919.

Application filed February 11, 1918. Serial No. 216,435.

To all whom it may concern:

Be it known that I, ALBERT F. FIFIELD, a citizen of the United States, residing at Newark, in the county of Essex and State of New Jersey, have invented certain new and useful Improvements in Stitch-Forming Mechanisms for Chain-Stitch Sewing Machines, of which the following is a specification, reference being had therein to the accompanying drawings.

This invention relates to single chain-stitch sewing machines of the well known rotary looper type disclosed, for example, in the United States patent to Willcox, No. 15 44,490, of September 27, 1864.

In machines of this type, as commonly constructed, it is essential to the formation of enchain loops that the work be fed in the direction in which the looper-beak moves 20 when in loop-seizing position, in order that the descending needle may pass in front of both limbs of the previously formed loop held spread by the looper, whereby the looper-beak may first seize the nascent 25 needle-loop and subsequently pass between the limbs of the previous needle-loop. These machines, therefore, while well adapted for straight-away sewing in the direction in which the looper-beak moves in seizing a 30 needle-loop, are practically inoperative when an attempt is made to sew while feeding the work in a direction transversely of the plane of rotation of the looper, the reason being that there is no provision for insuring that 35 the needle will descend in front of both limbs of the previously formed needle-loop and that the previous needle-loop will be held spread in a position such that the beak of the looper will pass into it as is essential to 40 the stitch-forming operation.

In constructing the machine disclosed in my United States Patent No. 1,226,963, of May 22, 1917, which represents an earlier attempt to utilize chain-stitch mechanism 45 of the rotary looper type in connection with a jogging work-holder, it was found necessary to vibrate the looper-shaft laterally and to make use of a fixed loop-detaining spur, into engagement with which the limbs of the 50 previous needle-loop were carried by bodily jogging movements of the looper; the said spur being disposed at the opposite side of the needle-path from the loop-spreading portion of the looper in its loop-seizing stage of 55 movement and serving to position the limbs

of the needle-thread loops uniformly regardless of the position of the last stitch; this mechanism being more fully disclosed in my Patent No. 1,147,386, of July 20, 1915.

Further experiments with my earlier machine have demonstrated that stitch-forming mechanism of the rotary looper type often breaks thread when an attempt is made at high speed operation and it has been ascertained that the thread breakage is often 60 caused by the whipping around in front of the looper-beak of the needle-loop which is cast off by the looper.

An object of the present invention is to improve and simplify the stitch-forming 70 mechanism disclosed in my said Patent No. 1,226,963 by eliminating the loop-detaining spur and the mechanism for producing bodily jogging movements of the looper, while retaining the feature of operativeness 75 when the work is fed transversely of the plane of rotation of the looper-beak.

Stated differently, an object of the present invention is to improve the well known single chain-stitch mechanism of the rotary 80 looper type, without resorting to complications, so that it will enchain the needle-loops properly and with certainty when the work is fed transversely of the plane of rotation of the looper-beak.

Another object of the invention is to provide a sewing machine having a jogging work-holder and stitch-forming mechanism of the rotary looper type adapted to form 90 detached groups of fastening stitches when the work-holder is given jogging movements transversely of the plane of rotation of the looper-beak.

Still further, the invention has for an object to improve stitch-forming mechanism 95 of the class described by overcoming the tendency of the cast-off needle-loops to whip around in front of and be caught by the looper-beak.

Further objects of the invention will appear 100 from the following description and claims.

To the attainment of these ends I have provided a looper of the rotary type having a loop-deflecting and spreading wing which, 105 together with the heel of the beak-forming portion of the looper, defines a throat into the bottom of which the loop seized by the looper is drawn and held spread for subsequent entry by the looper-beak after it has 110

2

seized a new needle-loop. I have so constructed and arranged the present looper relatively to the looper-shaft and needle that, during the descent of the needle-point 5 below the work, the bottom of the loop-spreading throat in the looper lies well to the side of the needle-path opposite to the side on which the looper-beak lies at this time. The throat of the present looper 10 serves, therefore, to position both limbs of the last needle-loop in a rearwardly and downwardly inclined position relatively to the needle-path, thus insuring that the descending needle will pass with certainty in 15 front of both limbs of said previous needle-loop, even though the work be fed transversely of the plane of rotation of the looper. In other words, I have fixed the looper-shaft in a position such that the needle-path lies 20 between the axis of rotation of the looper and the point of the looper-beak at the time when the needle point is piercing the work and I have so arranged the looper-body relatively to the axis of the looper-shaft that the 25 bottom of the loop-spreading throat lies entirely at the same side of the needle-path as the axis of the looper-shaft.

With this novel relative arrangement of the needle and looper it is found that, when 30 the work is fed or jogged back-and-forth transversely of the plane of rotation of the looper, the needle will always descend in front of the previous loop and that said previous loop will be held spread in a position 35 such that the looper will pass the new needle-loop through the previous needle-loop.

To control the needle-loops as they are being drawn up to the work, a device has been 40 provided which bears upon the substantially concentric outer edge of the beak-forming portion of the looper and detains each cast-off needle-loop until the point of the looper has advanced far enough and the loop has 45 been drawn up short enough to render it impossible for such loop to be again caught by the looper-beak. This device is particularly useful in combination with the present stitch-forming mechanism since the 50 point of the looper-beak is still moving upwardly as it passes the needle and, by the time the looper reaches cast-off position, the point of the looper-beak has not descended as far as in prior stitch-forming mechanisms 55 wherein the looper-point has a downward component of motion when it enters the needle-loop.

In the accompanying drawings, Figure 1 60 is a rear side elevation of a well known type of button sewing machine in which the invention has been embodied. Fig. 2 is a perspective view of the work-holder mechanism of the machine. Fig. 3 is a front end elevation of the stitching and work-holding mechanisms. Fig. 4 is an elevation of the

stitching implements similar to Fig. 3 but at the time the needle-point is entering the work. Fig. 5 is a perspective view of the needle, the looper and the stitching thread loops, when the work-holder is shifted toward the standard of the machine. Fig. 6 70 is a similar view of the parts when the work-holder is shifted toward the end of the work-arm. Figs. 7 and 8 are front end and front side elevations, respectively, of 75 the parts in the position shown in Fig. 5. Figs. 9 and 10 are front end and front side elevations, respectively, of the parts in the position shown in Fig. 6, and Fig. 11 is a detail perspective view of the loop-controlling 80 device shown in Fig. 3.

In the particular embodiment of the invention illustrated, the machine frame comprises a base 1 from which rises the hollow standard 2 of the bracket-arm provided with 85 the overhanging tubular portion 3 terminating in the head 4 in which is journaled the reciprocating needle-bar 5 carrying the eye-pointed needle 6. Extending forwardly from the standard 1 beneath the tubular 90 portion 3 is the work-supporting arm 7.

The present machine is provided with a work-clamp and operating mechanism therefor constructed substantially in accordance with the disclosure of my said Patent No. 95 1,226,963 and adapted to handle either two- or four-hole buttons. The work-clamp comprises the jogging bar 8 which extends longitudinally of and rests upon the work-arm 7. To the forward end of the bar 8 is secured 100 the fabric supporting plate 9 upon which rests the button-clamp comprising the opposed button-gripping jaws 10, 10, carried by the spring-pressed arm 11 secured upon the block 12 mounted upon the rearward end of the bar 8. The connections for imparting longitudinal movements to the work-clamp comprises the vertical post 13 rigidly sustained by the rearward end of 105 the bar 8 and embraced by a slotted arm 14 of a rock-lever fulcrumed at 15 to the bracket 15' bolted to the frame. The other arm 16 of the rock-lever carries a roller 17 which enters a suitable cam-slot 18 in the inner face of the usual cam-wheel 19 actuated, in a manner well known, by the main-shaft of the machine. An adjusting screw 20 is carried by the usual slide-block (not shown) which is adapted to be secured in various positions of adjustment on the post 120 13 to vary the amplitude of the longitudinal jogging movements of the work-holder.

Acting on the work-holder in a direction transversely of the work-arm 7 is the well known train of mechanism comprising the 125 slide-plate 21 secured to the bar 8 by dowel pins 22 and a screw 22* and carrying the downwardly extending pin 23 connected by a link 24 to one arm 25 of a bellerank-lever fulcrumed on a pin 26 sustained by the 130

work-arm 7. The other arm 27 of the bell-crank-lever is slotted to receive a headed pin 28 connected to one end of an adjustable link 29, the opposite end of which is freely connected to the lower end of an actuating member or lever 30 fulcrumed on the transverse pin 31 rigidly held in a socket formed in the bracket 15'. Pivoted to the lever 30 on the transverse pin 32' is a movable follower-element or arm 32 carrying at its upper end a laterally extending pin 33 on which is journaled a roller 34 adapted to enter a suitable cam-slot 35 in the outer face of the feed-wheel 19. The follower-element or arm 32 of the lever 30 carries a fulcrum-pin 36 which, when turned by the handle 37 acts through suitable mechanism fully described in my said Patent No. 1,226,963 to swing the arm 32 about the pivotal point 31 and withdraw the cam-roll 34 from the cam-slot 35, at the same time shifting the vertical pin 38 at the upper end of the arm 32 into engagement with the cam-slot 39 in the stationary arm 40 which serves to shift the work-clamp to a position half-way between the extremes of its jogging movements laterally of the work-arm when the follower-arm 32 is disengaged from the actuating cam-slot 35. As this mechanism forms a part of the prior art and is not claimed specifically herein, further description thereof is believed to be unnecessary. It may be stated, however, that at the beginning of a stitching cycle, when the present machine is adjusted to sew four-hole buttons, the cam-roll 34 lies in an inner concentric portion 35' of the cam-slot 35 and prevents movement of the work-clamp transversely of the work-supporting arm while the cam-slot 18 imparts jogging movements to the work-clamp alternately in opposite directions lengthwise of the work-arm to position the left-hand pair of eyes of the four-hole button for reception of fastening stitches. When the first group of stitches has been formed, the roll 34 enters an outer concentric portion 35'' of the cam-groove 35 and shifts the work-holder to the left, or to the position shown in Fig. 4, so that the two remaining eyes at the right-hand side of the center of the button may receive a group of fastening stitches. Thus it will be seen that all of the stitch-positioning movements of the work-holder during a complete stitching cycle are executed longitudinally of the work-arm with the exception of the single movement of the work-holder to the left, Fig. 3, to position the first stitch of the group formed through the right-hand pair of eyes of the button.

Journalized within and lengthwise of the work-arm 7 is the rotary looper-shaft 41 into the enlarged and socketed end of which is secured the shank 42 of the rotary looper formed with a loop-seizing beak 43 and with

the loop-deflecting and spreading wing 44. Between the heel 45 of the beak-forming portion of the looper and the wing 44 is a throat 46, the bottom of which affords a groove having forward and rearward extremities 47 and 48 serving to spread the forward and rearward limbs *a*, *b*, of the needle-loop seized by the looper.

Referring to Figs. 3, 4, 7 and 9, it will be seen that the axis of the looper-shaft 41 is placed well to the left of the needle-path and, furthermore, that the looper is so shaped and mounted on the looper-shaft that the extremities 47 and 48 of the loop-receiving and -spreading groove at the bottom of the throat 46 lie well to the left of the needle-path during the time the needle-eye is descending below the work. By virtue of this construction and arrangement of parts, the needle 6 is caused to descend, with certainty, in front of both limbs *a*, *b*, of the previous needle-loop whether said limbs extend downwardly from a previous stitch shifted rearwardly of the work-arm, as shown in Figs. 7 and 8, or forwardly of the work-arm, as shown in Figs. 9 and 10. The looper-beak will therefore seize the nascent needle-loop and pass it through the previous needle-loop regardless of the fact that the work is shifted transversely of the plane of rotation of the looper; the direction of movement of the looper beak in seizing a needle loop, being considered as a rearward movement.

A loop-controller 50 is provided for the purpose of preventing the cast-off needle-loop from whipping around in front of the looper-beak 43. In the present embodiment the loop-controller 50 is in the form of a thin flat spring having its upper extremity curved in conformity to and bearing upon the concentric outer edge-portion 51 of the beak-forming portion of the looper. The spring 50 is mounted upon a pin 52 which is adjustably held in a socket in the bracket-piece 53 screwed to the work-arm. The spring 50 will retain yielding control of the needle-loops being cast from the looper until the beak of the looper has passed safely beyond the possible range of movement of said loops as they are being drawn up to the work.

Inasmuch as the point of the loop-seizing beak of the present stitch-forming mechanism has an upward component of motion when it seizes the new needle-loop, said beak is inclined slightly toward the axis of rotation of the looper, so that the beak of the looper will lie more nearly at right angles to the needle when seizing a needle-loop than would otherwise be the case. This will be clear from an inspection of Fig. 3 wherein the dotted circular arc *c* concentric and coincident with the edge portion 51 of the looper serves as a reference line indicating

the amount of inward dip of the present looper-beak.

In the various figures the arrows indicate the directions in which the parts are moving:

5 Having thus set forth the nature of the invention, what I claim herein is:—

10 1. In a sewing machine, in combination, a reciprocating needle, a rotary looper-shaft, a looper formed with a loop-seizing beak and mounted on said shaft, and means for shifting the work transversely of the plane of rotation of said looper, the axis of rotation of said looper-shaft being displaced from intersecting relation with the needle- 15 path in the direction of movement of the looper-beak when seizing a needle-loop.

20 2. In a sewing machine, in combination, a reciprocating needle, a rotary looper-shaft, a looper formed with a loop-seizing beak and mounted on said shaft, a work-holder, feeding mechanism for imparting stitch-positioning movements to the work-holder in a direction transversely of the plane of rotation of said looper, the axis of rotation 25 of said looper-shaft being displaced from intersecting relation with the needle-path in the direction of movement of the looper-beak when seizing a needle-loop.

30 3. In a sewing machine, in combination, stitch-forming mechanism including a reciprocating needle and a rotary looper formed with a loop-seizing beak, a work-holder, and feeding mechanism for producing relative stitch-positioning movements 35 between said stitch-forming mechanism and work-holder in opposite directions transversely of the plane of rotation of said looper, the axis of rotation of said looper-shaft being displaced from intersecting relation with the needle-path in the direction 40 of movement of the looper-beak when seizing a needle-loop.

45 4. In a sewing machine, in combination, a reciprocating needle, a rotary looper-shaft, a looper carried by said shaft and formed with a loop-seizing beak and a loop-spreading wing, the axis of rotation of said looper-shaft being so arranged relatively to the needle-path and the loop-spreading wing 50 that the limbs of the previous needle-loop are held spread in a position leading downwardly from the last stitch and away from the needle-path in the direction of loop-seizing movement of the looper-beak, where- 55 by the needle will pass with certainty at the same side of both limbs of the last needle-loop and will lie intermediate the beak of the looper when in loop-seizing position and the limbs of the previous needle-loop when 60 the work is shifted transversely of the plane of rotation of the looper.

5. In a sewing machine, in combination, a reciprocating needle, a rotary looper-shaft, a looper carried by said looper-shaft and formed with a loop-seizing beak and loop- 65

spreading wing, the axis of rotation of said looper-shaft being so arranged relatively to the needle-path and the thread-engaging portions of the looper that the limbs of the previous needle-loop are held spread in a 70 downwardly and rearwardly inclined direction from the last stitch, whereby the needle will pass in front of the limbs of the last needle-loop when the work is shifted transversely of the plane of rotation of the looper. 75

6. In a sewing machine, in combination, a reciprocating needle, a rotary looper-shaft, a looper carried by said shaft and formed with a loop-seizing beak and a loop-spreading throat, and feeding mechanism for shifting the work transversely of the plane of rotation of the looper-beak, the axis of rotation of said looper-shaft being so arranged relatively to the looper and needle-path that the looper-beak and the bottom of 80 the loop-spreading throat will be disposed at opposite sides of the needle-path at the time the looper-beak is about to seize the nascent needle-loop.

7. In a sewing machine, in combination, a reciprocating needle, a rotary looper-shaft, a looper mounted on said shaft, said looper having a loop-seizing beak and a throat adapted to receive and spread a needle-loop seized by the looper, the axis of rotation of 90 the looper-shaft being so arranged relatively to the needle-path and the bottom of said throat that when the beak of the looper is in loop-seizing position the needle-path will lie between the looper-beak and the bottom 95 of said throat.

8. In a sewing machine, in combination, a reciprocating needle, a rotary looper-shaft, a looper mounted on said shaft, said looper having a loop-seizing beak and a throat 100 adapted to receive and spread a needle-loop seized by the looper, the point of said beak having an inward inclination or dip toward the axis of said looper-shaft and the axis of rotation of the looper-shaft being so arranged relatively to the needle-path and the bottom 105 of said throat that when the beak of the looper is in loop-seizing position the needle-path will lie between the looper-beak and the bottom 110 of said throat.

9. In a sewing machine, in combination, a reciprocating needle, a rotary looper having a loop-seizing beak and a loop-spreading throat and means for shifting the work transversely of the plane of rotation of the looper, the loop-spreading throat of the looper being so positioned and of a width such that the limbs of the previous needle loop are held spread in a downwardly and rearwardly inclined direction from the last 120 stitch and on opposite sides of the path of the looper beak when the latter is moving rearwardly in loop-seizing position.

10. In a sewing machine, in combination, a reciprocating needle, a rotary looper hav- 130

ing a loop-seizing beak and a loop-spreading wing, and a loop-controller coöperating with said looper when in cast-off position to control the needle-loops cast from the looper and thereby prevent said loops from whipping around in front of the beak of the looper when the machine is operated at high speed.

11. In a sewing machine, in combination, 10 a reciprocating needle, a rotary looper having a loop-seizing beak and a loop-spreading wing, and a loop-controller bearing yieldingly against the outer edge-portion of the loop-seizing beak when the looper is in cast-off position to control the needle-loops cast 15 from the looper and thereby prevent said loops from whipping around in front of the

beak of the looper when the machine is operated at high speed.

12. In a sewing machine, in combination, 20 a reciprocating needle, a rotary looper having a loop-seizing beak and a loop-spreading wing, and a loop-controlling spring bearing lightly against the looper when in cast-off position to control the needle-loops cast 25 from the looper and being drawn up to the work and thereby preventing said loops from whipping around in front of the beak of the looper when the machine is operated at high speed. 30

In testimony whereof, I have signed my name to this specification.

ALBERT F. FIFIELD.
